By *G. H. Conrad, Jr.* Attorney

UNITED STATES PATENT OFFICE.

GEORGE H. CONRAD, OF BINGHAMTON, NEW YORK.

ADVERTISING DEVICE.

1,263,211.

Specification of Letters Patent. Patented Apr. 16, 1918.

Application filed December 22, 1916. Serial No. 138,444.

To all whom it may concern:

Be it known that I, GEORGE H. CONRAD, a citizen of the United States, residing at Binghamton, in the county of Broome and State of New York, have invented certain new and useful Improvements in Advertising Devices; and I do hereby declare the following to be a full, clear, and exact description of the invention, such as will enable others skilled in the art to which it app pertains to make and use the same.

This invention relates to an advertising device and has for one of its objects, the provision of a device of this character, especially adapted for exhibiting advertising matter and also capable of exhibiting clothing and similar articles.

Another object of this invention is to provide means for causing the advertising matter to travel in a circular path and adapted to be alternately illuminated so as to attract attention.

Another object of this invention is to provide a rotating casing carrying the advertising matter and having secured thereto a figure for supporting or wearing clothing and similar articles.

A still further object of this invention is the provision of an advertising device of the above stated character, which shall be simple, durable and efficient, and which may be manufactured and sold at a comparatively low cost.

With these and other objects in view as will become more apparent as the description proceeds, the invention consists of certain novel features of construction, combination and arrangement of parts as will be hereinafter more fully described and claimed.

For a complete understanding of my invention, reference will be had to the following description and accompanying drawings, in which:—

Figure 1 is a vertical sectional view of an advertising device constructed in accordance with my invention, having the figure removed,

Fig. 2 is a longitudinal sectional view taken on the line 2—2 of Fig. 1,

Fig. 3 is a side elevation partly in section, 50 illustrating the figure applied to the casing,

Fig. 4 is a diagrammatical view of the wiring diagram,

Fig. 5 is a sectional view taken on the line 5—5 of Fig. 1.

Referring in detail to the drawings, the numeral 1 indicates a substantially circular base having an annular flange 2 formed thereon. A bearing 3 is formed centrally upon the base 1 and has mounted therein a vertical shaft 4. Upper and lower bearings 5 and 6 are secured to the vertical shaft 4 and have mounted thereon ball bearings 7 on which bear cones 8 secured to the ends of a cylindrical sleeve 9, which surrounds the shaft 4. The sleeve 9 has secured to its upper end, a supporting bracket 10 which is in turn secured to a casing 11 having an annular wall 12. The annular wall 12 is provided with oppositely disposed elongated openings 13 over which are secured frames 14 for supporting advertising matter.

Secured to the sleeve 9 is a spur gear 15 which meshes with a worm gear 16 carried by a shaft 17 that is journaled in a standard 18 carried by the base 1. The shaft 17 has secured thereto a pulley 19 which is connected to a pulley 20 of a motor 21 by a belt 22 for rotating the casing 11.

A circular housing 23 is secured to the top of the casing 11 for inclosing a block 24 having a cam face 25, which is secured to the top of the casing 11. A substantially U-shaped support 26 is secured to the base 1 and overlies the housing 23 as illustrated in Fig. 3. An operating rod 27 is pivoted to the web portion of the substantially U-shaped support 26 as illustrated at 28 and has pivotally secured to its free end a vertically extending rod 29 which extends through an aperture in the web portion of the support 26 and is connected to a figure 30 having its feet or lower end resting upon the web portion of the substantially U-shaped support 26. A friction roller 31 is secured on the operating rod 27 and is adapted to engage the cam face 25 of the block 24 as the same travels in the path of

a circle with the casing 11, causing the rod 29 to move upwardly and downwardly carrying the figure 30 therewith. The figure 30 may be covered or clothed with clothing 5 or similar articles for the purpose of advertising the same. It will be therefore noted that the figure will move upwardly and downwardly as well as being rotated with the casing 11, so as to thoroughly show off 10 the clothing or other articles thereon from all points.

The casing and the manner of mounting the figure are illustrated and claimed in my divisional application filed July 31st, 1917 15 and serially numbered 183,711.

An insulating sleeve 37 is mounted upon the sleeve 9 and held thereon by nuts 32, on which a contact ring or band 34 is mounted. A brush 35 is secured to a ring 36 mounted 20 upon the band 34 and engages contact plates 37 mounted upon an insulating block 38 carried by the base 1. A pole 39 is carried by the insulating block 38 and has secured thereto a brush 40 which engages the ring or band 25 34. An electrical plug 41 has the usual conductors 42 connected thereto for furnishing it with electrical current from any well known electrical source. A conductor 43 is connected to the plug 41 and to the pole 39. A conductor 44 is connected to one of the contact plates 37 and to an electric lamp 45 30 mounted upon the base and located within the casing 11. Connected to the electric lamp 45 is a conductor 46 which connects with a conductor 48 that in turn connects with a fuse 49. A conductor 50 is connected to the fuse 49 and to a switch 51. Connected to the switch 51 is a conductor 52 which is in turn connected to the plug 41, whereby a circuit 35 40 is closed to the electric lamp 45 when the switch 51 is closed and the brush 35 engages one of the contact plates 37. A conductor 53 is connected to the other contact plate 37 and is in turn connected to an electric lamp 54 located adjacent the electric lamp 45. A conductor 55 is connected to the electric lamp 54 and to the conductor 48, thus 45 50 when the switch 51 is closed and the brush 35 is in contact with the last mentioned contact plate 37, the electric lamp 54 will be illuminated. A conductor 56 is connected to the plug 41 and to a switch 57. A conductor 58 is connected to the switch 57 and to a fuse 59. A conductor 60 is connected 55 60 to the fuse 59 and to the motor 21. A conductor 61 is connected to the motor 21 and to the conductor 43 which is connected to the plug 41, whereby when the switch 57 is closed, an electric circuit is completed to the motor 21 causing the same to rotate the casing 11, and as the casing 11 rotates the brush 35 alternately engages the contact plates 37 and alternately illuminates the electric lamps 45 and 54, to illuminate the advertising

matter carried by the frames 14 of the casing 11. The contact plates 37 are so located upon the insulating block 38 that when the openings 13 in the casing and frames 14 move in front of the electric lamps 45 and 54, they are illuminated so as to illuminate 70 the advertising matter carried by the frames.

To prevent confusion of the drawings, the conductors have been omitted from the figures and it is thought that the construction will be understood by referring to the dia- 75 grammatical view of the wiring diagram.

A switch board 2' is secured to the base 1 for the purpose of supporting the switches 51 and 57.

From the foregoing description taken in 80 connection with the accompanying drawings, it will be noted that an advertising device has been provided whereby clothing and other articles may be readily exhibited as well as advertising matter, such as printing 85 and the like may be exhibited and illuminated.

If desired, the housing 23, block 24, and the substantially U-shaped support 26 and the element carried thereby may be removed 90 from the casing 11 and the figure secured in any well known manner permanently to the casing 11, whereby the figure will be turned within a circle by the casing 11, but will be minus of the upward and downward motion 95 rendered by the operating rod 27 and the rod 29.

While I have shown and described the preferred embodiment of my invention, it will be understood that minor changes in construction, combination and arrangement of parts may be made without departing from 100 the spirit and scope of the invention as claimed.

Having thus described my invention, what 105 I claim is:

1. An advertising device comprising a base, a shaft carried by said base, a sleeve rotatably mounted on the shaft, a casing carried by the sleeve, advertising matter carried 110 by the casing, means for rotating the sleeve, contact bands carried by the sleeve and insulated therefrom, an insulating block secured to the casing, a pole supported by said block, means for supplying electrical current 115 to said pole, a brush carried by said pole and engaging the bands, contact plates carried by the block, electric lamps located within the casing and electrically connected to the contact plates, and a brush carried by 120 the bands and adapted to engage the contact plates to alternately illuminate the electric lamps upon rotation of the casing.

2. An advertising device comprising a base, a sleeve rotatable on said base, means rotating the sleeve, a casing carried by the sleeve and having openings therein closed 125 by advertising matter, a ring carried by said

sleeve and insulated therefrom, a brush engaging the sleeve, a contact plate carried by said base, and a brush carried by the sleeve and engaging the contact plate to complete 5 an electric circuit to electric lamps for illuminating the advertising matter.

In testimony whereof I affix my signature in presence of two witnesses.

GEORGE H. CONRAD.
